J. GUMBER AND F. F. FEARHEILEY:
COMPENSATING DEVICE.
APPLICATION FILED JULY 16, 1921.

1,423,480.

Patented July 18, 1922.

UNITED STATES PATENT OFFICE.

JOSEPH GUMBER AND FRED. F. FEARHEILEY, OF EAST MOLINE, ILLINOIS, ASSIGNEES
TO AUTOMATIC TAKEUP NUT COMPANY, OF EAST MOLINE, ILLINOIS, A CORPORATION.

COMPENSATING DEVICE.

1,423,480.

Specification of Letters Patent. Patented July 18, 1922.

Application filed July 16, 1921. Serial No. 465,937.

To all whom it may concern:

Be it known that we, JOSEPH GUMBER and FRED. F. FEARHEILEY, citizens of the United States, residing at East Moline, in the 5 county of Rock Island and State of Illinois, have invented certain new and useful Improvements in Compensating Devices, of which the following is a specification, reference being had to the accompanying drawings.

This invention relates to certain improvements in compensating devices and has relation more particularly to a device of this general character especially designed and 15 adapted for use in connection with bearings or other structures where it is of advantage to take up lost motion, slack or wear on any machine or parts, and it is an object of the invention to provide a novel and improved 20 device of this general character comprising two separable members connected in a manner whereby one of said members may be caused automatically to rotate independent- 25 ly of the other and wherein the opposed faces of said members are provided with coacting means, when in working or applied position, to take up or compensate for wear.

The invention consists in the details of construction and in the combination and arrangement of the several parts of our improved compensating device whereby certain important advantages are attained and the device rendered simpler, less expensive and otherwise more convenient and advan- 35 tageous for use, as will be hereinafter more fully set forth.

The novel features of our invention will be hereinafter definitely claimed.

In order that our invention may be the 40 better understood, we will now proceed to describe the same with reference to the accompanying drawings, wherein:

Figure 1 is a fragmentary view partly in section and partly in elevation illustrating 45 compensating devices constructed in accordance with an embodiment of our invention and employed in connection with a connecting rod of an internal combustion engine or the like;

Figure 2 is a transverse sectional view taken through the inner member or washer as comprised in Figure 1;

Figure 3 is a view in bottom plan of said inner member or washer;

Figure 4 is a view in top plan of the outer member or nut as disclosed in Figure 1;

Figure 5 is a transverse sectional view taken through said outer member or nut;

Figure 6 is a fragmentary view in elevation, with a part in section, illustrating a compensating device constructed in accordance with a further embodiment of our invention;

Figure 7 is a fragmentary view in elevation illustrating a compensating device constructed in accordance with a still further embodiment of our invention, the coacting spring being omitted; and

Figure 8 is a view in plan of the outer end of the case for holding the relatively rotatable members against independent movement when being applied.

As disclosed in the accompanying drawings, S denotes a shaft with which is engaged a box 1 carried by the connecting rod 75 C or the like. Also engaged with the shaft S is a removable cap or bearing 2 which is secured in a conventional manner to the box 1 by the bolts 3. The bolts 3 extend beyond the outer face of the cap 2 and with each 80 extended portion is associated a compensating device constructed in accordance with an embodiment of our invention.

As disclosed in the accompanying drawings our improved compensating device 85 comprises two members A and B, the member A being of the type of a castle nut and its inner edge is provided with a series, preferably two in number, of teeth 4, corresponding edges of said teeth 4 being inclined or beveled, as at a, in the same general direction and to substantially the same extent. The member A is adapted to be threaded upon an extended portion of a bolt 3.

The member B comprises a washer which is adapted to freely surround the bolt 3, when in applied position, and the outer end or edge of said member B is also provided with a series of teeth 5, preferably two in number. 100 The teeth 5 have corresponding faces b inclined in the same general direction and substantially to the same extent, the inclination of the faces b being substantially complementary to the inclination of the faces a 105 of the teeth 4 of the member A.

6 denotes a coil spring which encircles the adjacent end portion of the members A and

B and one end portion of said spring 6 is engaged, as at 7, with the member A while the opposite end portion of the spring is engaged, as at 8, with the member B.

5 In practice, the members A and B, before being applied, are rotated one relative to the other to place the spring 6 under tension and the members A and B are then preferably snugly engaged within a case 9. The 10 case, as illustrated in Figure 8, is angular in cross section and the member A at its outer end portion is provided with a head 10 and the member B at its intermediate portion is provided with an outstanding 15 flange 11, said head 10 and flange 11 each having an angular periphery similar to the cross sectional configuration of the case 9.

After the members A and B have been arranged within the case 9, the member A is 20 threaded upon the extended portion of a bolt 3 with the washer or member B innermost. After proper application of these members, the case 9 is removed.

Upon wear of the box 1, the cap 2, the 25 shaft 8 or kindred parts, the tension of the spring 6 will impart rotation to the washer or member B and the coacting inclined or beveled faces a and b will readily and effectively compensate for such wear.

30 We also find it of advantage, after our improved compensating device has been applied, to employ the cotter pin 12 or the like through a bolt 3 outwardly of the applied device and through opposed recesses 10' in 35 the head 10 of the nut or member A. This is of particular advantage in the event the spring 6 should break, under which condition the cotter pin 12 will prevent the members A and B from coming apart and will 40 allow only the amount of slack which has been taken up by the member B.

The member A, in practice, is of a size 45 of the ordinary castle nut now used and, therefore, will not increase the amount of splash in the oil when used in gas engines and can also be used in places where the amount of clearance will not allow the use of other nuts without changing other parts of the machine. The member A can also be 50 made to fit any bolt or stud now in use and by having the member B loose on the coacting bolt or stud, said member B will not bind on said bolt or stud which is very apt to occur when a threaded nut is used in place 55 of the slip member B.

While a cotter pin 12 can be used to advantage, the nut or member A' may be locked to the bolt 3' or the like through the instrumentality of a set-screw 14, as illustrated in Figure 7.

In the embodiment of our invention as particularly illustrated in Figure 6, the same comprises three members. One of said members X is adapted to be threaded upon 65 the bolt 3^a or the like while the remaining

two members Y are loosely arranged upon said bolt 3^a inwardly of the member or nut X. Each of these members Y is of substantially duplicate construction and are provided with the opposed teeth 15 having their 70 outer faces inclined in the same general direction and substantially to the same extent. Associated with the members Y and surrounding the opposed ends of the same is a coil spring 6', said spring and members Y 75 cooperating in the same manner and for the same purposes as has hereinbefore been set forth with respect to the spring 6 and the members A and B.

The outer end of the case 9 is provided at 80 substantially diametrically opposed points with the inwardly disposed wings or flanges 16 so that when said case is applied to the members comprised in our compensating device, said device is prevented from passing 85 entirely therethrough which would otherwise impede or handicap the application of the device into a working position.

From the foregoing description it is thought to be obvious that a compensating 90 device constructed in accordance with our invention is particularly well adapted for use by reason of the convenience and facility with which it may be assembled and operated, and it will also be obvious that our 95 invention is susceptible of some change and modification without departing from the principles and spirit thereof and for this reason we do not wish to be understood as limiting ourselves to the precise arrangement 100 and formation of the several parts herein shown in carrying out our invention in practice except as hereinafter claimed.

We claim:

1. A compensating device of the class described comprising two members, said members having rotation one relative to the other when applied to the work, opposed faces of the members being provided with beveled portions adapted to contact, a spring co-acting with said members to automatically rotate the members one with respect to the other, and means engageable with the members for holding the same against relative rotation before being applied to the work. 105

2. A compensating device of the class described comprising two members, one of said members being adapted to be threaded to its work, the other being free thereon, the opposed faces of the members being provided with bevel portions, and a member connecting the first two members and placed under tension upon relative rotation of the first two members, in combination with a case to receive the first two members after 110 the same have been relatively rotated to place the second named member under tension, said case and first named members having co-acting means to hold the first two members within the case against relative 115 rotation. 120

125

130

rotation under the influence of the second named member.

3. A compensating device of the class described comprising two members, one of said members being adapted to be threaded to its work, the other being free thereon, the opposed faces of the members being provided with bevel portions, and a member connecting the first two members and placed under tension upon relative rotation of the first two members, in combination with a case to receive the first two members, after the same have been relatively rotated to place the

second named member under tension, said case and first named members having co-
15 acting means to hold the first two members within the case against relative rotation under the influence of the second named member, said case at one end having an inwardly directed wing to prevent the first 20 named members when applied within the case from passing entirely through the case.

In testimony whereof we hereunto affix our signatures.

JOSEPH GUMBER.

FRED. F. FEARHEILEY.
